UNITED STATES PATENT OFFICE.

JULIUS E. WATEROUS AND JAMES N. PEEL, OF BRANTFORD, ONTARIO,
CANADA.

PULLEY.

SPECIFICATION forming part of Letters Patent No. 295,698, dated March 25, 1884.

Application filed February 5, 1884. (No model.)

To all whom it may concern:

Be it known that we, JULIUS E. WATEROUS and JAMES N. PEEL, subjects of the Queen of Great Britain, both residing at Brantford, in 5 the Province of Ontario, Canada, have invented a new and useful Improvement in Pulleys, of which the following is a specification.

This invention relates to an improvement in that class of belt-pulleys which are designed 10 to revolve at a high rate of speed; and it has for its object to produce a strong and light pulley, in which the arms and rim are constructed of wrought-iron or steel, and which can be easily balanced.

15 Our invention consists, to that end, of the improvements in the construction of the pulley, which will be hereinafter fully set forth, and pointed out in the claims.

In the accompanying drawings, consisting 20 of two sheets, Figure 1 is a side elevation of our improved pulley. Fig. 2 is a section in line $x-x$, Fig. 1. Fig. 3 is a sectional elevation of the outer edge of one of the arms and connecting parts. Fig. 4 is a plan view of the 25 arm-head. Figs. 5 and 6 are sectional elevations of modified constructions of the means whereby the arms are secured to the rim.

Like letters of reference indicate like parts in the several figures.

30 A represents the hub of the pulley; B, the arms, and C the rim. The arms B are constructed of wrought-iron or steel, and flattened or otherwise enlarged at their inner ends, as represented in Fig. 2, so that upon placing the 35 inner ends of the arms in the mold of the hub and casting the latter on the arms the latter will be firmly secured to the hub. The arms may be secured in the hub by keys or other suitable means; but we prefer to cast them in 40 the hub, as it makes a simpler and stronger connection.

D represents the arm-heads, which are attached to the outer ends of the arms and secured to the inner side of the rim. The heads 45 D are made hollow, and fit with their open outer ends against the inner side of the rim C. Each head is provided with projecting ears d, which are secured to the same by rivets d'.

As represented in Figs. 1, 2, and 3, the 50 outer end of each arm is provided with an

external screw-thread, e, which engages in an internally-threaded sleeve, E, seated in a bore of the head D, and provided at its outer end with a flange, f, which engages against a shoulder, f', at the bottom of the cavity G of 55 the head D.

H represents a jam-nut applied to the threaded end of the arm, and bearing against the inner end of the sleeve E. The inner end of the sleeve E, which projects beyond the 60 bore of the head D, is made hexagonal, or otherwise constructed so that the sleeve can be turned by a winch. When the arms B have been cast in the hub A, the heads D and sleeves E are applied to the outer ends of the 65 arms and adjusted with reference to the axis of the pulley. The rim C is then riveted to the heads D, whereby the pulley is completed. If the speed of the pulley is so high that the 70 centrifugal force will cause a considerable outward pressure on the arms, this pressure is compensated for by adjusting the sleeves E inwardly until a sufficient inward pressure is applied to the rim and arms to balance the outward pressure produced by the centrifugal 75 force. If the pulley is not balanced when the rim has been applied, holes i are drilled through the rim opposite one or more of the cavities G of the heads D, on the light side of the pulley, and the cavities G are filled with molten 80 lead or other suitable metal until the pulley is balanced.

In the construction represented in Fig. 5 the sleeve E is applied to the outer side of the head D by means of an internal screw-thread 85 formed in the sleeve E, and an external screw-thread formed on the inner portion of the head D. The sleeve E is in this case secured on the outer end of the arm B by the jam-nut H on the inner side of the sleeve, and a jam-nut, H', applied to the arm B in the cavity of the sleeve, between the latter and the inner 90 end of the head D.

In the construction represented in Fig. 6 the threaded outer end of the arm B is screwed 95 directly into the threaded opening of the head D and locked by the jam-nut H. The arms B are preferably made tapering from the hub toward the rim, to render them light and strong.

The rim may be constructed of one or more 100

parts, according to the size of the pulleys, and the arm-heads *D*, which are applied to the joints of the rim, are arranged with their ears *d* at right angles to the joint, to firmly connect 5 the ends of the rim-sections, as represented at *j* in Fig. 1. The edges of the rim-sections are further secured together by strips *k*, riveted to the inner sides of the rim.

We claim as our invention—

- 10 1. The combination, with the hub *A*, of arms *B*, rigidly secured thereto, adjustable heads *D*, applied to the outer ends of the arms, and a rim, *C*, secured to the heads *D*, substantially as set forth.
- 15 2. The combination, with the hub *A*, of arms *B*, rigidly secured thereto, heads *D*, arranged at the outer ends of the arms, sleeves *E*, whereby the heads *D* are adjustably secured to the arms, and a rim, *C*, secured to the heads 20 *D*, substantially as set forth.

3. The combination, with the hub *A* and rim *C*, of arms *B*, rigidly secured to the hub, and having their outer ends provided with external screw-threads, heads *D*, secured to the inner side of the rim, and sleeves *E*, constructed 25 with internal screw-threads, and having flanges *f* at their outer ends bearing against the sleeves, substantially as set forth.

4. The combination, with the hub *A*, arms *B*, and rim *C*, of heads *D*, connecting the rim 30 to the arms, and constructed with cavities adapted to receive counterbalancing material, substantially as set forth.

Witness our hands this 31st day of January, 1884.

JULIUS E. WATEROUS.
JAMES N. PEEL.
